Inventor
John F. Gail

By Offield, Towle, Graves & Soans Atty:

UNITED STATES PATENT OFFICE.

JOHN F. GAIL, OF EVANSTON, ILLINOIS, ASSIGNOR TO SIMMONS COMPANY, OF KENOSHA, WISCONSIN, A CORPORATION OF DELAWARE.

CORNER FASTENING.

Application filed August 21, 1919. Serial No. 318,881.

To all whom it may concern:

Be it known that I, JOHN F. GAIL, a citizen of the United States, residing at Evanston, in the county of Cook and State of Illinois, have invented certain new and useful Improvements in Corner Fastenings, of which the following is the specification.

My invention has reference more particularly to a lock or fastening device which is adapted to be used in furniture construction, for detachably connecting the end of a frame member to the side of a post, as for example, in bed construction, wherein an angle iron side rail of the bed is connected to the post of the bed end.

The principal objects of my invention are, to provide improved means for detachably securing the end of a longitudinal member of angular cross section, such as an angle iron, in a socket; to enable such a member to be conveniently secured in the socket in reversed positions; to enable such reversed connection to be made without removing or reversing the locking means; to provide a locking device having a toggle action or relatively swinging parts for effecting the clamping engagement of the longitudinal member in the socket; to provide a device of this character wherein the locking parts remain assembled in the socket when the longitudinal member is released; and in general to provide improved locking means which is simple and inexpensive, and which may be conveniently operated to securely clamp the end of an angle iron or similar member in a socket.

On the drawings, Fig. 1 is a side view of a fragmentary portion of a post and angle iron connected therewith, in accordance with my invention;

Fig. 2, an enlarged view on the line 2—2 of Fig. 1, with the angle iron shown in transverse section;

Fig. 3, a perspective view of the swinging members which effect the locking engagement; and

Fig. 4, a perspective view of the clip for holding the two swinging parts of the locking member together.

As shown on the drawings, the reference numeral 1 indicates a fragmentary portion of a post, such as the post of a bed end, and 2 a fragmentary portion of an angle iron, such as the angle iron side rail of a bed,

which is detachably connected to the post 1. 55 For the purpose of affording such connection the post 1 is provided with a bracket or socket member 3 on the side thereof, which may be of any suitable form or construction and secured to the post in any desired manner. This socket in the construction shown comprises a plate bent in inverted U-shape, with the edges of the two legs 7 secured against the side of the post, and the connecting wall 4, between the upper ends 60 of the legs formed so as to provide square corners adapted to have the corner of an angle iron fitted therein. Spaced from the upper wall 4 is a cross plate 5, which has depending ears 6 secured to the side walls 70 or legs 7 of the bracket, to provide a substantially rectangular housing or socket 8 at the upper end of the bracket. This socket is adapted to have the end of the angle iron 2 inserted therein in the position shown in 75 full lines in Fig. 2, or in the reverse position as shown by the dotted lines at 9 in Fig. 2.

For locking the end of the angle iron in the socket 8, in either of these positions, I so have provided a locking member or device comprising a pair of expansible elements 10, operated by a wing nut 11, threaded on a bolt 12, said bolt being inserted transversely through the lateral walls of the socket 8, 85 substantially mid-way between the top and bottom walls 4 and 5, respectively, thereof, as shown in Fig. 2. The head 13 of this bolt engages against the outer side of one of the walls 7 and the wing nut 11 is threaded 90 on the opposite end of the bolt at the outer side of the socket wall, with the sleeve 14, loosely telescoped on the stem of the bolt 12, and interposed between the wing nut 11 and the locking elements 10, to apply pressure from the wing nut to said elements. The wall of the socket 8 adjacent the wing nut has a large perforation 15, through which the sleeve 14 projects, as shown in Fig. 2.

The locking elements 10 in the assembled form constitute an arched member, centrally split at 16, to permit relative swinging movement or toggle action of the parts 10 thereof, along the line of juncture 16, when pressure is applied by the wing nut 11 and sleeve 14 to the backs of the two elements 10. The outer ends of the elements 10 are round-

ed at 17 to afford in effect a roller or enlarged end for clamping engagement with the angle iron 2. The two parts 10 are correspondingly notched at each end, as indicated at 5 18, adjacent the juncture line 16 and the clip 19, laid against the backs thereof, and provided with inturned ears 20, which engage in the notches 18 and are hooked on their inner ends against the inner faces of 10 the elements 10, so as to hold the two parts 10 together as a unit, while permitting the necessary relative movement thereof, for locking the angle iron in the socket. This clip 19 is preferably bent inwardly along the top 15 and bottom edges, as at 21, to apply a spring pressure against the backs of the elements 10, to hold them normally in retracted position.

As hereinbefore stated, the angle iron 2 may be inserted in the socket 8 in either of 20 the positions shown by the full lines and dotted lines in Fig. 2, and the opening 22, which is formed, one-half in each of the parts 10, and also the corresponding opening 25 23 in the clip 19, is vertically elongated, as clearly shown in Figs. 3 and 4, to permit the necessary shifting of the locking parts 10, to accommodate either placement of the angle iron 2 in the socket 8.

When the angle iron is inserted in position, and pressure applied to the elements 10, by turning the wing nut 11, the two elements 10 are forced against the vertical flange of the angle iron, and when engaged 30 thereagainst, further tension on the elements 10 by the wing nut 11 effects a toggle action or relative swinging movement of the elements 10, along the line 16, and this action spreads the outer ends of the respective elements 10 apart, so that in addition to direct pressure of the locking elements 10 in the direction of the length of the bolt 12, there is also a pressure upwardly by the upper element 10, and downwardly by the lower 45 element 10, which forces the vertical flange 24 of the angle iron into close frictional engagement with a side wall of the socket 8, and the horizontal flange 25 of the angle iron against the upper or lower wall as the 50 case may be, of the socket 8. Obviously, the elongated openings 22 and 23 of the locking elements 10 and the plate 19 permit the locking device to automatically adjust itself between the upper and lower surfaces engaged thereby. When pressure is released 55 from the locking members 10, the spring flanges 21 of the clip 19 return the members 10 to the contracted relative position, so that the angle iron 2 may be readily withdrawn or inserted.

To obviate the necessity of removing the bolt 12 when inserting the nail, the upright flange 24 of the angle iron is preferably slotted, as indicated at 23, in Fig. 1. Both 60 ends of the rail or angle iron are slotted in

this manner, to permit reversal of the rail, as such reversal is effected by the turning of the angle iron 2 end for end, and inserting the other end in the socket 8.

While I have described my invention in a particular form, I am aware that various changes and modifications may be made without departing from the principles of my invention, and I therefore do not propose to limit the patent granted hereon otherwise than as necessitated by the prior art. 75

I claim as my invention:

1. In a corner fastening, the combination of a post having a socket extending laterally therefrom, a member of angular cross section having an end adapted to be inserted in said socket, and means for detachably clamping the end of the member in the socket, said means comprising an actuator 80 and a pair of clamping members on opposite sides respectively of the actuator and operable thereby to swing relatively and thereby clamp the end of said member in the socket. 85

2. In a corner fastening, the combination of a post having a socket extending laterally therefrom, a rail having an end adapted to be inserted in the socket, and locking means in the socket comprising a plurality of toggle members, and means for effecting relative movement thereof, to clamp the end of the rail in the socket. 90

3. In a corner fastening, the combination of a post having a socket extending laterally therefrom, an angle iron having an end adapted to be inserted in the socket, and a locking device for clamping the end of the angle iron in the socket, comprising spaced bearings engaging one flange of the angle iron and means adapted to apply pressure intermediate of said bearings and thereby clamp the end of the angle iron in the socket. 100

4. In a corner fastening, the combination of a post having a socket extending laterally therefrom, an angle iron having an end adapted to be inserted in the socket, and means for clamping the end of the angle iron in the socket, comprising a member 110 adapted to be intermediately bowed and thereby clamp said end in the socket. 115

5. In a corner fastening, the combination of a post having a laterally extending socket and an angle iron having an end adapted to be inserted therein, and locking means in the socket comprising a pair of levers adapted to co-operate to apply pressure against both flanges of the angle iron, to clamp the same in a corner of the socket. 120

6. In a corner fastening, the combination of a post having a laterally extending socket and an angle iron having an end adapted to be inserted therein, and a locking device in the socket comprising a pair of pivotally 130

- related members, means for holding said members together, and means for effecting pivotal movement of such members to bear against both flanges of the angle iron and thereby lock the angle iron in the socket. 5
7. In a corner fastening, the combination of a post having a laterally extending socket and an angle iron having an end adapted to be inserted therein, and locking means in the socket comprising a plurality of relatively movable members, operable to lock the angle iron in the socket, and resilient means acting upon release of the locking members to automatically return the locking members to the initial position. 10
8. In a device for fastening an angle iron to a post, the combination of abutments on the post adapted to be engaged by the flanges of the angle iron, and a pivoted member having a portion thereof which is disposed laterally from the pivotal axis, pressed against the angle iron intermediate of the flanges so as to clamp each flange of the angle iron against its respective 15 abutment.
9. In a device for fastening an angle iron to a post, the combination of abutments on the post adapted to have the flanges of the angle iron clamped thereagainst, a shiftable bearing, a locking member having a rocking action against said bearing, and means for simultaneously shifting the bearing and the locking member toward the angle iron so as to rock the locking member in a plane transverse to the length of the angle iron and thereby clamp the flanges of the angle iron against said abutments. 20
10. In a device for fastening an angle iron to a post, the combination of abutments on the post adapted to have the flanges of the angle irons clamped thereagainst, a locking member adapted to swing on an axis parallel with the longitudinal axis of the angle iron and means for shifting said axis laterally so as to cause the locking member to pivotally engage the angle iron at the juncture of the flange thereof and thereby clamp each flange of the angle iron against its respective abutment. 25
11. In a device for fastening an angle iron to a post, the combination of a pair of abutments against which the flanges of the angle iron are adapted to be clamped, locking means comprising a pair of swingingly combined members having bearing portions at their ends, and means for applying pressure to said members so as to change the angular relation thereof and thereby separate the end bearing portions so as to clamp the angle iron against the abutments. 30
12. In a device for fastening an angle iron to a post, the combination of a pair of abutments and a fixed member on the post, an angle iron, a pair of swingingly related arms, one of which has an end engaging the angle iron between the flanges, and the other of which has an end engaging the fixed member and the outer edge of one of the flanges of the angle iron, and means for swingingly adjusting said arms so as to cause the aforesaid ends to apply pressure simultaneously to the angle iron for clamping the latter against the abutments. 35
13. In a device for fastening an angle iron to a post, the combination of a socket extending laterally from the post, a transverse bolt in the socket, an angle iron having the end thereof inserted in the socket so that the flanges thereof engage against adjacent sides of the socket, and a pair of loosely connected locking arms extending on opposite sides of the bolt, and operable thereby for clamping the angle iron in the socket. 40
14. In a device of the class described, the combination with an angle iron, of an end fastening therefor comprising a pair of abutments adapted to receive the angle iron cornerwise therebetween, a third abutment, and a locking member slidable transversely of the angle iron on the third abutment and tilttable thereon so as to clamp the flanges of the angle iron against the pair of abutments. 45
15. In a device of the class described, the combination of an angle iron having a pair of angularly related flanges, and an end fastening for the angle iron comprising a pair of abutments adapted to receive the angle iron cornerwise therebetween, and a locking member having spaced portions differentially operable against one of the flanges of the angle iron so that one portion exerts pressure to clamp said flange against its abutment and the other portion simultaneously exerts pressure to clamp the other flange against its abutment. 50
16. In a device of the class described, the combination with an angle iron of means to which the end of the angle iron is adapted to be secured comprising a pair of abutments arranged to receive the angle iron cornerwise therebetween with each flange of the angle iron engaged respectively against its corresponding abutment, a locking means having a pair of spaced projections engaging the same flange of the angle iron at laterally spaced points so that one of the projections applies pressure to clamp said flange against its abutment and the other projection applies pressure to clamp the other flange against its abutment, and threaded means for applying pressure to the locking means intermediate of said projections. 55

JOHN F. GAIL.
